Primary Examiner — Susan Bennett Hattan*Assistant Examiner* — Marie Fast Horse(74) *Attorney, Agent, or Firm* — Carol N. Green Kaul, Esq.(57) **CLAIM**

The ornamental design for a portable communication device with a display, as shown and described.

DESCRIPTION

FIG. 1 is a front perspective view of the invention.

FIG. 2 is a bottom perspective view of the invention.

FIG. 3 is a front view of the invention.

FIG. 4 is a rear view of the invention.

FIG. 5 is a top side view of the invention.

FIG. 6 is a bottom side view of the invention.

FIG. 7 is a left view of the invention; and,

FIG. 8 is a right view of the invention in use.

1 Claim, 4 Drawing Sheets(56)
